UNITED STATES PATENT OFFICE.

EMORY E. LAMB, OF PULASKI, VIRGINIA.

FRESH-AIR CONVEYER.

941,370.

Specification of Letters Patent. Patented Nov. 30, 1909.

Application filed May 4, 1908. Serial No. 430,775.

To all whom it may concern:

Be it known that I, EMORY E. LAMB, a citizen of the United States, residing at Pulaski, in the county of Pulaski and State of Virginia, have invented a new and useful Fresh-Air Conveyer, of which the following is a specification.

This invention relates to fresh air conveyers, and more particularly to that type of devices of this character utilized for conveying fresh air to the mouth of a person sleeping within a closed room.

The object of the invention is to provide a simple form of device of this character having a tubular skeleton frame of novel form which cannot collapse at any point and thus retard the circulation of air and which is provided with a removable fabric covering which can be readily detached and cleaned whenever desired.

Another object is to provide a hood designed to cover the head of the sleeper without retarding the movements thereof, said hood being of sufficient size to permit a free circulation of pure and impure air into and from it.

A further object is to provide simple means for attaching the circulation tubes to the window casing, said means being adjustable to windows of different sizes.

With these and other objects in view, the invention consists of certain novel features of construction and combination of parts which will be hereinafter more fully described and pointed out in the claims.

In the accompanying drawings the preferred form of the invention has been shown.

In said drawings:—Figure 1 is a view, partly in section and partly in elevation, of the complete apparatus. Fig. 2 is an enlarged detail perspective view of a portion of the skeleton frame of one of the tubes. Fig. 3 is an enlarged section through one of the fasteners employed for attaching the inlet tube to the hood. Fig. 4 is a detail view of the extensible panel used within the window casing, one of the parts of this panel being broken away.

Referring to the figures by characters of reference, 1—1 designate superposed rings made of spring wire or other suitable material, said rings being of different diameters and arranged to form a cone-shaped skeleton frame, the adjoining rings being connected by oppositely-disposed inclined connect-

ing links 2 formed of spring wire or other similar material. Extending from the apex of this frame is the skeleton frame of the outlet tube of the apparatus, said skeleton frame consisting of a series of rings 3 formed preferably of spring wire and connected by oppositely-disposed inclined links 4 also formed of spring wire. These rings are held by the links spaced apart predetermined distances at all times. It will be seen, therefore, that the skeleton frame of the hood and outlet tube are formed in one continuous part. Mounted on these two frames is a casing consisting of a suitable close-mesh fabric, said casing comprising an elongated tubular member 5 and a conical member 6, said conical member being disposed to extend over the rings 1 of the conical frame, while the tubular member 5 extends over the rings 3 and their connections. The conical portion 6 of the casing extends beyond the lower or larger spring 1 to form a circular apron 7 designed to hang loosely about the head of the user so as to prevent the admission of air to the hood from the surrounding atmosphere.

An opening 8 is formed within the conical casing 6 near the bottom or open end thereof, and arranged about this opening are fasteners of any desired form. In the drawings socket-members 9 of the well known ball-and-socket fastener type have been shown secured to the conical casing 6. The socket members 10 of these fasteners are secured to the flared end 11 of a fabric casing 12 arranged upon the skeleton frame 13 of the inlet tube of the apparatus. This skeleton frame is similar in all respects to the frame within the casing 5. It will be apparent, of course, that by snapping the fastener members 10 onto the members 9 the frame 13 and casing 12 can be firmly fastened to the hood casing 6. Both of the tubular casings 5 and 12 have their free ends surrounding metallic thimbles 12'; and these casings may be detachably secured to the thimbles in any preferred manner by means of elastic bands 14 or other securing devices. Each thimble 12 is designed to project through an opening 15 formed within a panel 16, and this panel has an extension 17 slidably mounted thereon and held in proper relation thereto in any preferred manner as by means of guide cleats 18. If preferred, a screen 19 of any desired form

may be arranged transversely within each of the thimbles 12.

In using the device herein described, one panel 16 and its extension is placed within 5 the window casing A and above one of the window sashes B, while another panel 16 and its extension is placed within the window casing and below the other sash. The thimble 12 of the inlet tube is then inserted 10 into the opening 15 in the lower panel while the thimble 12 in the outlet tube is inserted in the opening in the upper panel. Said lower tube is then attached to the hood 6 in the manner described, and the apparatus is 15 then ready for use. The hood is placed over the head of the user and the apron 7 will obviously rest upon the uneven surface 20 of the bed and prevent the admission of any part of the surrounding atmosphere to the interior of the hood. Each inhalation of the user will cause an amount of fresh air to be drawn through the lower or inlet tube and into the hood and the vitiated air will 25 be expelled subsequent to each exhalation through the upper or outlet tube because of the fact that it is lighter than the fresh air admitted through the lower tube. As the hood is comparatively large it will not interfere with the movements of the head therein 30 and no discomfort therefore will be experienced by the user.

When it is desired to clean the casings 5, 6 and 12, the casing 12 is detached from the casing 6 and can then be slipped off of the 35 skeleton frame 13 and the casings 5 and 6 can also be removed from the frames contained therein. After they have been washed and dried in any preferred manner they can be readily replaced, as will be obvious.

40 It is of course to be understood that when the device is not in use the skeleton frames can be folded into compact bundles and each panel 16 and its extension 17 collapsed so that the entire apparatus will occupy a comparatively small space.

45 The device is very simple, durable and efficient and will be found particularly beneficial to persons suffering from tuberculosis

and similar diseases requiring fresh air in the treatment thereof.

50

What is claimed is:—

1. Apparatus of the character described comprising a hood, an outlet tube extending therefrom, and an inlet tube detachably connected to the hood, each tube and the hood 55 comprising a frame and a removable casing.

2. Apparatus of the character described comprising a hood, an outlet tube extending upwardly therefrom, an inlet tube detachably connected to the lower portion thereof, 60 each tube and the hood comprising a flexible skeleton frame, and a covering therefor.

3. Apparatus of the character described comprising a hood, an inlet tube extending from the lower portion thereof, an outlet 65 tube extending from the upper portion thereof, each tube and the hood consisting of spaced elastic rings, elastic connecting links between the rings, and a removable fabric casing.

4. Apparatus of the character described comprising a hood, inlet and outlet tubes extending therefrom each tube and the hood consisting of a spring skeleton frame and a casing removably mounted upon the frame, 75 a thimble detachably secured within one end of each tube, and an apertured panel for the reception of each thimble.

5. Apparatus of the character described comprising a hood, flexible inlet and outlet 80 tubes extending therefrom each tube consisting of spaced rings, spring connections therebetween, and a removable fabric casing surrounding the rings and connections, a thimble extending into one end of each tube, 85 means for detachably securing each tube to its thimble, and an extensible panel having apertures for the reception of the respective thimbles.

In testimony that I claim the foregoing as 90 my own, I have hereto affixed my signature in the presence of two witnesses.

EMORY E. LAMB.
